UNITED STATES PATENT OFFICE

99,032

DESIGN FOR A CORDUROY FABRIC

Nat Karson, New York, N. Y., assignor to Crompton Company, West Warwick, R. I., a corporation of Rhode Island

Application December 21, 1935, Serial No. 60,224

Term of patent 7 years

To all whom it may concern:

Be it known that Nat Karson, a citizen of the United States, residing at New York, in the county of Manhattan and State of New York, has invented a certain new, original, and ornamental Design for Corduroy Fabric, of which the following is a specification, reference being had to the accompanying drawing, forming a part thereof.

The drawing is a plan view of a corduroy fabric showing my new design.

The present design comprises as the principal and dominating features thereof a plurality of foot ball players each kicking a foot ball over a goal post, arranged over the face of the fabric and in which the direction in which the foot ball players kick is varied, as shown.

I claim:

The ornamental design for a corduroy fabric substantially as shown and described.

In testimony whereof I affix my signature.

NAT KARSON.
